FREDERICK S. GALLAGHER, OF COLLINWOOD, OHIO, ASSIGNOR, BY MESNE ASSIGNMENTS, TO WAUGH DRAFT GEAR COMPANY, A CORPORATION OF ILLINOIS.

DRAFT AND BUFFING MECHANISM FOR RAILWAY-CARS.

1,218,642.

Specification of Letters Patent.

Patented Mar. 13, 1917.

Application filed March 30, 1906. Serial No. 308,911.

To all whom it may concern:

Be it known that I, FREDERICK S. GALLAGHER, a citizen of the United States, residing at Collinwood, in the county of Cuyahoga and State of Ohio, have invented certain new and useful Improvements in Draft and Buffing Mechanism for Railway-Cars, of which the following is a specification.

This invention relates to draft and buffing mechanisms for railway cars, and pertains more especially to that class or type of such devices which require a comparatively wide range of lateral or angular movement of said parts on account of short and sharp curves in the track. More specifically, the invention belongs to that class of devices in which the buffing mechanism partakes bodily of the lateral movement of the draw-bar, and maintains a substantially constant relation to the latter as regards lateral or angular movement.

Among the leading objects of the invention are to provide a mechanism capable of a wide range of angular movement, and in which the buffer plates of adjacent cars may maintain parallelism and contact under all conditions; to dispense with the usual equalizer bar and one set of side stems; to provide improved means of attaching the safety chains; to provide an improved means of uniting the parts of a sectional draw-bar; and, in general, to provide a reliable and efficient mechanism of the character specified representing a relatively low cost of construction and maintenance.

To these ends the invention consists in the matters hereinafter described and more definitely pointed out in the claims.

My invention, in an approved mechanical form, is illustrated in the accompanying drawings, wherein,—

Figure 1 is a top plan view of the draw-bar, draft-rigging, and buffing mechanism, illustrating also a means whereby the draw-bar and draft-rigging may be laterally actuated from the truck;

Fig. 2 is a longitudinal sectional view of the same; and

Fig. 3 is a cross-sectional view on the offset line 3—3 of Fig. 1.

Referring to the drawings, 5 designates a longitudinal sill, and 6 an end sill of a car underframe, and 7 and 7^a designate transverse I-beams forming hangers or carrier ends for the draw-bar and buffing mech-

anism. Somewhat inwardly of the forward end of the car-frame is located what I term the draft-rigging, the same comprising, in the simple form shown, the usual stop castings 8, front and rear followers 9 and 10, 60 resistance spring 11, and yoke 12, the forward end of which latter is pivotally connected as by a pivot-bolt 13 to the rear end of the draw-bar 14, which latter is herein shown as of considerable length, and as 65 consisting of forward and rear sections 14^a and 14^b connected end to end, as indicated at 14^c in Fig. 2, this being for convenience and economy in removing either section, especially the forward one, when necessary 70 by reason of injury or wear, without disturbing the other. The two sections are united by upper and lower straps 15 and 16, respectively, which overlap both sections to a considerable extent, and are united 75 thereto by through-bolts 17 and rivets 18.

Secured to and embracing the forward section of the draw-bar, slightly in rear of the coupler head 19 is what I term the buffer-supporting frame; the same consisting, preferably, and as herein shown, of an upper casting 20 overlying the upper strap 15 transversely thereof, and a generally U-shaped casting 21 rigidly secured beneath the same as by bolts 22 and embracing the draw-bar and straps, as clearly shown in Fig. 3. At the ends of the casting 20 are formed pockets 23 to accommodate the buffer springs 24, said pockets being opened on their outer sides to facilitate the 90 lateral insertion of the springs. Disposed forwardly of the pockets 23 are guides 25 to accommodate the side stems 26 of the buffing mechanism, said stems at their rear portions being shouldered for engagement 95 with followers 27 which in turn abut against the forward ends of the buffing springs, said stems having integral reduced portions or rods 26^a extending axially through the springs and through the rear ends of the 100 pockets, and retaining-nuts 28 and lock-nuts 29. The forward ends of the stems 26 have lateral extensions 30 that are apertured, as shown at 31, for the connection thereto of the safety chains 32, and the forward ends of said stems, inwardly of the lateral extensions, are pivotally connected by the usual buffer-plate 33.

The mechanism above described, when connected or coupled with the similar mech- 110

anism on an adjacent car, swings freely substantially into the line of draft between the pivotal points of the respective draw-bars, and, when disengaged, may be moved 5 either manually, or by any suitable centering or controlling device, such as the truck-actuated connection herein indicated as consisting of extensible connections 34 and 34^a between the draw-bar and the opposite 10 sides of the truck, portions of the frame of the latter being indicated at 35 and 35^a.

From the foregoing it will be seen that the entire supporting and carrying mechanism of the buffer-plate 33 is carried by 15 and swings angularly with the draw-bar; while the side stems 26 fit their guides 25 with sufficient looseness to allow either stem to be forced inwardly independently of the other on curves, whereby to preserve the 20 substantial parallelism of the contacting buffer-plates. The straps 15 and 16 form a strong and simple means for connecting the sections of a two-part draw-bar, which latter construction is of advantage in permitting either section, and particularly the 25 forward section, to be removed and replaced when necessary without disturbing the rear section and the draft-rigging connected thereto. The lateral extensions of the side 30 stems of the buffer mechanism form convenient points of attachment of the safety chains 32, and, in case the latter are called into action through injury or uncoupling of the coupler members, their pull is exerted 35 through the buffer-supporting frame, draw-bar, and draft-rigging.

I claim:

1. In a draft and buffing mechanism, the combination with a draw-bar, of a buffer 40 casting overlying the same and secured

thereto, said casting having lateral pockets for the buffer springs, a depending casting secured to said overlying casting and embracing the draw-bar, buffer springs in said pockets, side stems engaging said springs, 45 and a buffer-plate pivoted to the forward ends of said side stems, substantially as described.

2. In a buffing mechanism, the combination of a buffer-supporting frame, of buffer 50 springs mounted in either side thereof, side stems engaging said springs, a buffer-plate, connected to the forward ends of said side stems, and means for the attachment of safety chains to the forward ends of said 60 side stems, substantially as described.

3. In a buffing mechanism, the combination with a buffer-supporting frame, of buffer 65 springs in either side thereof, side stems engaging said springs and having apertured lateral projections for the connection of the safety chains, and a buffer-plate connected to and between the forward ends of said side stems, substantially as described.

4. In a buffing mechanism for railway 70 cars, the combination of a buffer-supporting frame, a buffing cushion, a buffer-stem connection engaging the same, and a safety chain co-acting with said stem connection, substantially as described. 75

5. In a buffing mechanism for cars, the combination of a buffer supporting frame, a pair of buffing cushions, buffer stem connections engaging the same, and safety chains co-acting with the said stem connections, substantially as described. 80

FREDERICK S. GALLAGHER.
